(57) **CLAIM**

The ornamental design for a color correction applique as shown and described.

DESCRIPTION

FIG. 1 is a top, front, right side perspective view of a color correction applique according to the present disclosure, shown in an environment of use.

FIG. 2 is a front view of the color correction applique of FIG. 1.

FIG. 3 is a rear view of the color correction applique of FIG. 1.

FIG. 4 is a top view of the color correction applique of FIG. 1, the bottom view being a mirror image thereof; and, FIG. 5 is a right side view of the color correction applique of FIG. 1, the left side view being a mirror image thereof. The broken lines in FIGS. 2 and 3 depict portions of the color correction applique that form no part of the claimed design. The additional broken lines shown in FIG. 1 depict environmental subject matter and form no part of the claimed design.
